FIG. 1

FIG. 2

FIG. 3

FIG. 4

FIG. 5

FIG. 6

FIG. 7

FIG. 8

FIG. 9

FIG. 1 is a perspective view of a support arm for a luminaire or the like embodying my new design; FIG. 2 is a side elevational view; FIG. 3 is a top plan view; FIG. 4 is a bottom plan view; FIG. 5 is an end elevational view; FIG. 6 is the other end elevation; and FIGS. 7, 8, and 9 are sections thereof taken on lines 7—7, 8—8, and 9—9 respectively of FIG. 3.

The other side is substantially the same as the one shown in FIG. 2.

The dominant features of my design are shown in solid lines.

The broken line showing of the reflector, globe and wall attaching clamp in FIG. 1 is for illustrative purposes only.

I claim:

The ornamental design for a support arm for a luminaire or the like, as shown and described.
